UNITED STATES PATENT OFFICE.

AURE O. BOUVIER, OF CLAREMONT, NEW HAMPSHIRE.

METAL-CUTTING MECHANISM.

1,412,652.

Specification of Letters Patent. Patented Apr. 11, 1922.

Application filed October 12, 1921. Serial No. 507,341.

To all whom it may concern:

Be it known that I, AURE O. BOUVIER, a citizen of the United States, residing at Claremont, in the county of Sullivan and State of New Hampshire, have invented certain new and useful Improvements in Metal-Cutting Mechanism, of which the following is a full, clear, and exact specification.

My invention relates to metal cutting mechanism.

It has for its object to provide an improved metal cutting mechanism of the oxy-acetylene or electric-arc pantograph type. A further object of my invention is to provide such an improved mechanism wherein the guiding element operatively connected to the pantograph may be readily moved from place to place upon the table more expeditiously and with less effort on the part of the operator and wherein all damage or scarring of the table calculated to interfere with subsequent operations and arising from dragging of the traction wheel, may be eliminated.

In the accompanying drawings I have shown for purposes of illustration one embodiment which my invention may assume in practice.

In these drawings,—

Fig. 1 is a plan view of a cutting mechanism.

Fig. 2 is a partial sectional view substantially on line 2—2 of Fig. 1.

In this illustrative construction I have shown a cutting mechanism of the oxy-acetylene type including a pantograph comprising cooperating arms 1, 2, 3, and 4 suitably pivotally connected in a well known manner and movable relative to a pivot 5 over a frame 6 on which the work is supported, a cutter mechanism 7 of a usual type being provided on the arm 3 and supplied with a suitable mixture of oxygen and acetylene from tanks 8 and 9 respectively, through suitable pipes. As in a usual construction, the pantograph is also motor operated, the same being driven by a motor 10 carried on a bracket 11 on the usual projecting end of the arm 2, the bracket 11 in turn being supported on a suitable traction wheel support 12 in which a usual milled traction wheel 13 is journaled, the latter being adapted to be moved over a table 14 and relative to a suitable pattern on that table under the power of the motor and the guidance of the operator to move the cutter mechanism

7 through a similar path relative to the work carried on the table 6. Herein it will be noted that the traction wheel is rotatable by the motor only in one direction, the motor 10 carrying on its armature shaft 15 a worm 16 which meshes with the worm gear 17 on the upper end of a vertical shaft 18 journaled in the member 12 and carrying a worm 19 on its lower end which meshes with a cooperating worm gear 20 journaled on a transverse axis 21 on the member 12 and carrying concentrically with it a spur gear 22 which meshes with a corresponding spur gear 23 on the traction wheel 13.

In the operation of such a construction, wherein the traction wheel is rotated only in one direction by the motor, certain advantages arise from the simple form of driving mechanism required and the elimination of any necessity for motor control or reversing mechanism. However, when the operator has moved the traction wheel to the desired limit in the given direction, due to the locking of the worm gearing it is impossible for the average operator to draw the traction wheel back over the table 14 without dragging it upon the table and thereby materially increasing the effort required, unduly delaying the movement of the cutter to another position, and at the same time as a result of this dragging movement, scarring the table to such an extent as in a very short time to interfere with subsequent accurate movement of the traction wheel relative to the guides or patterns placed on the table and to require the purchase of a new table, which being of carefully finished metal is quite expensive.

These difficulties are removed as a result of my invention wherein it will be noted that a bracket 24 projects laterally from the lower end of the member 12 and carries on a pivot 25 near the outer end of the bracket, a member 26, herein for example carrying a roller 27 on its lower end, which member is adapted to be thrown down into the position shown in full lines in Fig. 2 to elevate and support the traction wheel and thereby provide a transport member or trolley therefor whenever desired. More particularly, it will be noted that the member 26 cooperates with a stop 28 disposed adjacent the pivot 25, the stop preferably being so disposed as to limit the movement of the member 26 to the right as shown in Fig. 2 and thereby cooperate with the member to pro-

vide a rigid support, the weight of the motor and the other parts carried upon the member 12 acting to press the member 26 against the stop and any movement of the 5 frame toward the left from the position shown in Fig. 2 also acting to press the member 26 against the stop. In a preferred form the member 26 is also provided with suitable means normally holding the same 10 in an inoperative position, the same herein including a coiled spring 29 connected to the member between its ends and to a laterally extending portion of the bracket 24. Thus, it will be observed that the spring 15 constantly tends to make the member 26 occupy the position indicated in dotted lines, while when the member 26 is thrown to the right, the weight of the parts tends to prevent the spring from moving the member. In order 20 to cooperate with the member 26 and prevent movement of the same beyond a desired inoperative position I also provide a suitable stop adapted to limit the movement of the member, this stop being herein in the form 25 of a lug 30 formed on the upper end of the member 26 and adapted to engage with the stop 28 when the member 26 has reached its desired inoperative position.

As a result of my improvement, it will be 30 observed that whenever it is desired to move the pantograph in a reverse direction it is only necessary to throw down the member 26 from its dotted to its full line position, whereupon the wheel 13 is automatically 35 raised out of contact with the table 14 in such a manner that an operator may move the pantograph expeditiously and freely in the reverse direction and without any scarring whatsoever of the table. Thus with 40 my improvement not only is the work of the operator materially facilitated and the possible usefulness of the machine in a given time speeded up, but the wear and tear on the table is eliminated thereby eliminating 45 the difficulties heretofore experienced in operating on a scarred table and also eliminating the frequent replacements of the expensive table which have heretofore been necessary. It will of course be evident that 50 whenever it is desired again to resume the traction movement it is only necessary to pull out the member 26 in order to lower the traction wheel 13 into contact with the table, the member 26 then being held by its spring 55 29 in its inoperative position out of the way of the operator.

While I have in this application specifically

described one embodiment which my invention may assume in practice, it will be understood that this form of the same is shown 60 for purposes of illustration and that the invention may be modified and embodied in various other forms without departing from its spirit or the scope of the appended claims.

What I claim as new and desire to secure 65 by Letters Patent is:

1. Cutting apparatus comprising a pantograph mounted cutter mechanism including a traction motor and a traction wheel rotatable thereby, a table normally engaged 70 by said traction wheel, and trolley means for said traction wheel engageable at will with said table.

2. Cutting apparatus comprising a pantograph mounted cutter mechanism including 75 a traction motor and a traction wheel rotatable thereby, a table normally engaged by said traction wheel, and trolley means for said traction wheel engageable at will with said table and including an adjustably 80 mounted roller carrying member.

3. Cutting apparatus comprising a pantograph mounted cutter mechanism including a traction motor and a traction wheel rotatable thereby, a table normally engaged by 85 said traction wheel, and normally inoperative trolley means for said traction wheel engageable at will with said table and including an adjustably mounted roller carrying member.

4. Cutting apparatus comprising a pantograph mounted cutter mechanism including a traction motor and a traction wheel rotatable thereby, a table normally engaged by 95 said traction wheel, trolley means for said traction wheel engageable at will with said table and including a movable roller carrying member adjustably mounted adjacent said wheel, and stop means for limiting the movement thereof.

5. Cutting apparatus comprising a pantograph mounted cutter mechanism including a traction motor and a traction wheel rotatable thereby, a table normally engaged by 105 said traction wheel, trolley means for said traction wheel engageable at will with said table and including a movable roller carrying member, resilient means normally holding said member in inoperative position, and stop means for limiting the movement of 110 said member.

In testimony whereof I affix my signature.

AURE O. BOUVIER.
